UNITED STATES PATENT OFFICE

129,385

DESIGN FOR A DRESS

Albert B. Weinberg, Merrick, N. Y.

Application August 1, 1941, Serial No. 102,614

Term of patent 3½ years

To all whom it may concern:

Be it known that I, Albert B. Weinberg, a citizen of the United States and a resident of the city of Merrick, in the county of Nassau and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress shown in Fig. 1.

I claim:

The ornamental design for a dress, substantially as shown.

ALBERT B. WEINBERG.
